UNITED STATES PATENT OFFICE.

HAAKON A. MARTIN, OF DAYTON, OHIO, ASSIGNOR TO THE NATIONAL CASH REGISTER COMPANY, OF DAYTON, OHIO.

DESIGN FOR A REGISTER CABINET OR CASING.

50,841.

Specification for Design.

Patented May 29, 1917.

Application filed June 10, 1916. Serial No. 103,036. Term of patent 14 years.

To all whom it may concern:

Be it known that I, HAAKON A. MARTIN, a citizen of the United States, residing at Dayton, in the county of Montgomery and State of Ohio, have invented a new, original, and ornamental Design for Register Cabinets or Casings.

Of the accompanying drawings forming part of this specification:

Figure 1 is a three-quarters front perspective from the left of the register cabinet or casing having the design of the present invention.

Fig. 2 is a three-quarters rear perspective from the right of the same register cabinet or casing.

What is claimed is:—

The ornamental design for a register cabinet or casing as shown.

In testimony whereof I affix my signature.

HAAKON A. MARTIN.
